UNITED STATES PATENT OFFICE.

STANLEY M. PONTIERE, OF PHILADELPHIA, PENNSYLVANIA.

AUTOMOBILE-SIGNAL.

1,348,182.

Specification of Letters Patent.

Patented Aug. 3, 1920.

Application filed February 17, 1919. Serial No. 277,563.

To all whom it may concern:

Be it known that I, STANLEY M. PONTIERE, a citizen of the United States, residing at Philadelphia, in the county of Philadelphia and State of Pennsylvania, have invented certain new and useful Improvements in Automobile-Signals, of which the following is a specification.

The invention relates to improvements in vehicle signals and has for its object to provide means for indicating the various movements of a vehicle.

Another object of the invention is to provide a signal device having sign plates which act conjointly to indicate the movement or prospective action of a vehicle.

With the above and other objects in view, which will be pointed out in the following specification, I have invented the device illustrated in the accompanying drawings, in which—

Figure 1 is an elevation of one form of the invention.

Fig. 2 is a detail elevation of a sign plate,

Fig. 3 is a similar view of another sign plate,

Fig. 4 is a section on line A—A, Fig. 1 when completely closed,

Fig. 5 is an end elevation of the device,

Fig. 6 is an elevation of another form of the invention,

Fig. 7 is a detail elevation of a sign plate,

Fig. 8 is a similar view of another plate,

Fig. 9 is a similar view of two plates,

Fig. 10 is an elevation of the device showing a sign plate in operative position, and

Fig. 11 is a section on line B—B, Fig. 6.

Like reference characters indicate like parts throughout the following specification and in the several views in the drawings in which 1 indicates one form of my signal, which consists of a casing 2 held by a bracket 3 to a windshield 4 or any other convenient part of an automobile or other vehicle. Pivotaly mounted at 4 in the case 2 is a plurality of signal plates 5, 6 and 7, each having a different sign thereon such as "Turn," "Slow," "Stop," etc., to indicate what action is about to be taken by the vehicle other than going straight ahead at ordinary speed. The plates 5, 6 and 7 are controlled by springs 8, 9 and 10 adapted to normally hold the plates thrown out of the case and are held in the case by means of

55 catches 11, 12 and 13 engaging the lugs 14, 15 and 16 on said plates. By pressing either

of said catches, the plates are released to be thrown out to exposed position by the controlling springs.

The plate 6, which is marked with the sign "Turn," has a large centrally disposed opening therein in order to expose the sign "Slow" on the center of plate 5, whereby the two signs "Turn" and "Slow" may be indicated at one and the same time, thus indicating that the vehicle is to turn and will slow down in making the turn, thus warning traffic behind how to proceed. A mirror 17 is provided on the near side 18 of the case in order that the driver may see what is behind his vehicle.

Each of the sign plates should have a back ground of a different color, each color indicating the same thing as the sign word, in order that the driver of a vehicle in the rear may know the meaning of the particular sign exposed even if he is too far behind to read the word or if he cannot read.

In Figs. 6 to 11, I show a modification of the invention in which slidable plates 19, 20 and 21 are provided in the case 22. Handles 23, 24 and 25 are provided on the plates respectively and each handle has a sign to conform to the sign on its plate.

Having now described my invention, that which I claim to be new and desire to procure by Letters Patent is:—

1. A vehicle signal consisting of a plurality of alining sign plates, one of which has an opening to expose a sign therebehind, and a casing in which the plates are mounted.

2. A vehicle signal consisting of a plurality of alining sign plates, one of which has an opening to expose a sign therebehind, and a casing in which the plates are mounted, and handles rigidly connected to each plate whereby one or two of the plates are projected from this casing.

3. The described device consisting of a casing and a plurality of flat sign plates mounted within the casing, and rigidly connected handles for said plates, whereby they may be manually moved to project outwardly of said casing, signs on all of said plates and means whereby signs on two plates may be exposed at one and the same time, said means consisting of an opening in one of said plates.

4. A vehicle signal embracing a plurality of flat sign plates and a casing therefor, one of said plates having an opening therein to expose a sign on another of said plates.

5. The described device consisting of a casing and a plurality of flat sign plates mounted within the casing, and rigidly connected handles for said plates, whereby they 5 may be manually moved to project outwardly of said casing, signs on all of said plates and means whereby signs on two plates may be exposed at one and the same time, said means consisting of an opening in 10 one of said plates, and the sign on another of said plates arranged in alinement with said opening.

6. A vehicle signal consisting of a plurality of alining sign plates, one of which 15 has an opening to expose a sign therebehind, and a casing in which the plates are mounted, and handles rigidly connected to each plate whereby one or two of the plates are projected from this casing, said plates 20 being pivoted to the casing.

7. A signal embracing a plurality of flat sign plates arranged one in front of the other and means for exposing signs on more than one of said plates at a time, said means 25 consisting of an opening in one of said plates.

8. A signal embracing a plurality of flat sign plates arranged one in front of the

other and means for exposing signs on more than one of said plates at a time, said means 30 consisting of an opening in one of said plates, said plates being spring controlled.

9. A signal embracing a plurality of flat sign plates arranged one in front of the other and means for exposing signs on more 35 than one of said plates at a time, said means consisting of an opening in one of said plates, said plates being spring controlled and means for holding the plates against the action of its spring.

10. A vehicle signal consisting of a plurality of alining sign plates, one of which has an opening to expose a sign therebehind, and a casing in which the plates are mounted, and handles rigidly connected to 45 each plate whereby one or two of the plates are projected from this casing, said plates being pivoted to the casing, and reversible upon being projected from the casing.

In testimony whereof I affix my signature 50 in the presence of two witnesses.

STANLEY M. PONTIERE
